DESIGN FOR A RADIO CABINET

Umberto Tecca, Bridgeport, Conn., assignor of
one-half to Eli Don Bullian, Greenbelt, Md.

Application February 12, 1947, Serial No. 136,876

Term of patent 7 years

(Cl. D56—4)

To all whom it may concern:

Be it known that I, Umberto Tecca, a citizen of the United States, residing at 483½ North Avenue, in the city of Bridgeport and State of Connecticut, have invented a new, original, and ornamental Design for a Radio Cabinet, of which the following is a specification, reference being had to the accompanying drawings, forming part thereof.

Figure 1 is a perspective view of a radio cabinet showing my new design.

Fig. 2 is a view similar to Fig. 1 with the cabinet top and lid moved to open position.

Fig. 3 is a perspective view of the back of the cabinet.

The characteristic features of my design reside in the portions shown by means of full lines in the drawing.

I claim:

The ornamental design for a radio cabinet, as shown and described.

UMBERTO TECCA.
